UNITED STATES PATENT OFFICE.

MEYER KAMENSTEIN, OF NEW YORK, N. Y.

ASH SIFTER.

1,415,575.

Specification of Letters Patent.

Patented May 9, 1922.

Application filed July 28, 1921. Serial No. 488,120.

To all whom it may concern:

Be it known that I, MEYER KAMENSTEIN, a citizen of the United States, and resident of New York city, in the county of Kings 5 and State of New York, have invented certain new and useful Improvements in Ash Sifters, of which the following is a specification.

The invention relates to an ash sifter of 10 the type which includes a barrel top for fitting over the top of the ash barrel and a sifter member rockably mounted thereon and enclosed by a cover.

The primary object of the invention is to 15 minimize the cost of such devices and incidental to this general desideratum further objects of the invention are to provide a simplified structure of relatively few parts, organized so that the parts will tend to mutually reinforce and brace each other without necessarily providing parts for this particular purpose.

Still another object of the invention is to 20 provide an ash sifter which can be easily manipulated to effect the sifting operation and from which the sifter cinders may be readily dumped. Further it is required that leakage of ashes into the outer air or 25 overflowing of the same into the ash barrel be minimized, if not entirely eliminated.

Various other objects and advantages of 30 the invention will be in part obvious from an inspection of the accompanying drawings and in part will be more fully set forth in 35 the following particular description of one form of mechanism embodying my invention, and the invention also consists in certain new and novel features of construction and combination of parts hereinafter set 40 forth and claimed.

In the accompanying drawings:

Figure 1 is a view of an ash barrel in side elevation showing a preferred embodiment 45 of the invention installed therein, in a closed and in an operative sifting position and with parts broken away to show internal construction;

Figure 2 is a view similar to Figure 1 showing the cover open and the parts in the 50 position of dumping the cinders from the sifter member;

Figure 3 is a transverse sectional view taken on the line 3—3 of Figure 1 looking 55 in the direction indicated by the arrow; and Figure 4 is a plan view looking down upon

the device shown in Figure 1 and with the cover in open position.

In the following description and in the claims, parts will be identified by specific names for convenience of expression but they 60 are intended to be as generic in their application to similar parts as the art will permit.

There is disclosed an ash barrel 10 of conventional structure on which is mounted an ash barrel top 11 preferably designed so as 65 to have a close fit and thus minimize leakage between the ash barrel and the top. The top is provided centrally thereof with a rectangular opening 12. The portion of the top outlining the opening is reinforced by 70 encircling the same about a reinforcing wire 13. The lapping edges 14 outlining the opening are interrupted at opposite sides to expose the wire and thus constitute bearings 15 and 16 and the portion of the top to 75 the outside of each bearing and in line therewith is cut away to provide apertures 17 and 18. The top is also provided to the outside of the aperture 18 with a hanger 19 in the form of an upwardly facing hook which 80 depends downwardly from the plane of the top, as shown in Figure 1 and provides a support for an ash receptacle 20 herein shown to be a bucket. The barrel top 11 is also provided with a flat cover 21 having extensions looped about exposed portions of the reinforcing wire 13 to form a hinge connection for the cover. It will be understood 85 from this construction that the single reinforcing wire not only acts to reinforce the 90 portion of the cover top outlining the opening but also constitutes the bearing for supporting the sifter member and constitutes the hinge pin for the cover.

The sifter member 22 is of substantially 95 semi-cylindrical form and includes oppositely disposed inclined ends 23 and 24 and a top outlining edge 25 together with screening material 26 disposed therebetween. The top edge 25 of the sifter member is of the 100 same rectangular configuration as the opening, is disposed substantially in the plane of the barrel top and fits the opening so that overflow material in the sifter member will not leak into the ash barrel between the 105 sifter member and the adjacent portion of the barrel top.

It is appreciated that the element of manufacturing cost in devices of this kind is vital to the perfection of a commercially 110

acceptable device and accordingly it is made of as thin grade of stock material as is possible. In order to reinforce the sifter member when so constructed there is disclosed a 5 reinforcing rod 27 which extends between the ends 23 and 24 so as to maintain the same braced in spaced apart position. The portions of the rod at opposite ends of the reinforcing portion are formed into looped members 28 and 29 which overlap the adjacent ends, overhang the bearings and thus provide a means for supporting the sifter member in oscillatory position. Each of the loop members include an inner part 29' which extends along and engages the inner face of the adjacent wall and is held thereto by straps 30 riveted to the ends. An outer portion 31 of each looped member extends downwardly into the apertures 17 and 18 to complete the loop. The end of the reinforcing rod at the end forming the loop 29 is again bent back upon itself so as to form an S-shape part 32, the free end of which projects upwardly past the cover to form a rocking 20 handle 33. The opposite end of the rod is extended downwardly for some material distance below the upper edge of the sifter so as to provide a relatively long hinge member 34. This hinge member 34 has a length 25 approximately equal to the distance between the bearing 16 and the outer edge of the barrel top, so that the sifter member can be raised bodily from the opening and moved into tilted position to dump the contents 30 thereof into the ash receptacle 20.

By means of a device such as is disclosed it is possible to provide a simple, inexpensive and reinforced structure which can be stamped to shape and assembled practically 40 without the use of skilled labor and without any necessity for refined machining.

While I have shown and described, and have pointed out in the annexed claims, certain novel features of my invention, it will 45 be understood that various omissions, substitutions and changes in the form and details of the device illustrated and in its operation may be made by those skilled in the art without departing from the spirit of the 50 invention.

Having thus described my invention, I claim:

1. An ash sifter comprising a barrel top provided with an opening, a reinforcing 55 wire encircled by the portion of the barrel top outlining the opening, a sifter member depending below said opening and provided with hooks at opposite sides thereof and hung on said reinforcing wire thereby to 60 suspend the sifter member for oscillatory movement and a cover hinged to said reinforcing member for closing said opening with the sifter in place.

2. An ash sifter comprising a barrel top 65 provided with an opening, a reinforcing

wire encircled by the portion of the barrel top outlining the opening, a sifter member depending below said opening and provided with hooks at opposite sides thereof and hung on said reinforcing wire thereby to suspend the sifter member for oscillatory movement and a cover hinged to said reinforcing member for closing said opening with the sifter in place, and a handle projecting upwardly through the cover from the sifter for 75 oscillating the same. 70

3. An ash sifter comprising a barrel top provided with an opening and having bearings at opposite sides of the opening, a sifter member provided with loop members at 80 opposite sides for engaging the bearings and thus mount the sifter members for oscillatory movement about an axis extending between the bearings and across the opening, one of said loop members coacting with its bearing to form a hinge connection and the other loop member being free to be lifted from its bearing whereby the sifter member may be swung from the opening thereby to dump its contents. 85

4. An ash sifter comprising a barrel top provided with an opening and having bearings at opposite sides of the opening, a sifter member provided with loop members at 90 opposite sides for engaging the bearings and thus mount the sifter members for oscillatory movement about an axis extending between the bearings and across the opening, one of said loop members coacting with its bearing to form a hinge connection and the other loop member being free to be lifted from its bearing whereby the sifter member may be swung from the opening thereby to dump its contents. 95

5. An ash sifter comprising a barrel top provided with an opening and having bearings at opposite sides of the opening, a sifter member provided with loop members at 100 opposite sides for engaging the bearings and thus mount the sifter members for oscillatory movement about an axis extending between the bearings and across the opening, one of said loop members coacting with its bearing to form a hinge connection and the other loop member being free to be lifted from its bearing whereby the sifter member may be swung from the opening thereby to dump its contents and a hanger secured to the barrel top adjacent said hinge connection 105 and adapted to support an ash receptacle for receiving the dumpings from the sifter member. 110

5. An ash sifter comprising a barrel top provided with an opening and having bearings at opposite sides of the opening, a sifter member provided with loop members at 115 opposite sides for engaging the bearings and thus mount the sifter members for oscillatory movement about an axis extending between the bearings and across the opening, one of said loop members coacting with its bearing to form a long hinge connection extending from the top of the sifter member down the adjacent side for a distance approximately equal to the distance from the opening to the outer edge of the barrel top, and the other loop member being free to be lifted from its bearing whereby the sifter member may be swung from the opening 120 thereby to dump its contents. 125

6. In an ash sifter, the combination of a flat barrel top having an opening with bearings at opposite ends thereof and in the plane of the top, a sifter member positioned in said 130

opening with its top disposed normally in the plane of said top and substantially closing the opening to prevent overflow from the sifter member leaking past the barrel 5 top, extensions from opposite sides of the sifter member demountably engaging said bearings to hang the sifter member for oscillatory movement and for permitting the removal of all parts of the sifter member from 10 the opening.

7. In an ash sifter, the combination of a barrel top having an opening and a pair of apertures on opposite sides of the opening, the portion of the top between each aperture 15 and the opening providing a bearing, a sifter member disposed within the opening and extending below the same, loop members at opposite ends of the sifter member resting on the bearings and with an inner part of 20 each secured to the sifter member and an outer part passed downwardly through the adjacent aperture.

8. In an ash sifter, the combination of a barrel top having an opening and a pair of 25 apertures on opposite sides of the opening, the portion of the top between each aperture and the opening providing a bearing, a sifter member disposed within the opening and extending below the same, loop members at 30 opposite ends of the sifter member resting on the bearings and with an inner part of each

secured to the sifter member and an outer part passed downwardly through the adjacent aperture, and one of said outer parts projecting downwardly to form a relatively 35 long hinge connection with the engaged bearing thereby to permit the sifter member to be raised bodily from the barrel top and out of the opening while maintaining a physical connection between the barrel top 40 and the movable sifter member.

9. In an ash sifter, the combination of a barrel, a top therefor, said top having an opening, a sifter member in said opening, a reinforcing rod extending across the sifter 45 member to brace the same, the portion of the rod at opposite sides of the sifter member being each bent upon themselves into loop members pivotally engaging the top.

10. In an ash sifter, the combination of a 50 barrel top having an opening, a sifter member in said opening, a reinforcing rod extending across the sifter member to brace the same, the portion of the rod at one end of the rod being bent into a loop and the 55 other end being bent into an S to form a loop and a handle.

Signed at New York city in the county of New York and State of New York this 21st day of July, A. D. 1921.

MEYER KAMENSTEIN.
